CONTAINER

Harry N. Falk, Chicago, Ill., assignor to Baxter Laboratories, Inc., Glenview, Ill., a corporation of Delaware

Application February 26, 1936, Serial No. 65,873

3 Claims. (Cl. 215—95)

This invention relates to a container and particularly to a container in which solutions, such as intravenous solutions, are carried.

A primary object of the invention is to provide a container having improved sealing means and a sealing cap therefor which can be readily removed. Other specific objects and advantages will appear as the specification proceeds.

The invention is illustrated in a preferred embodiment by the accompanying drawing, in which—

Figure 1 is a plan view of a sealing cap embodying my invention; Fig. 2, a sectional view of said cap and sealing parts applied to the neck of a bottle, the section being taken as indicated at line 2 of Fig. 1; Fig. 3, a perspective view of said cap; Fig. 4, a perspective view of a metal sealing disk; Fig. 5, a perspective view of a flexible sealing disk; Fig. 6, a perspective view of the inner clamping ring; and Fig. 7, a plan view of the sealing cap shown in opened position.

In the illustration given, the container B may be of any suitable type or size. As shown more clearly in Fig. 2, the bottle is provided with a neck 60 having ribs or threads 61 extending therearound. A rubber plug 62 is seated within neck 60, and is preferably provided with a top annular flange 63 resting upon the top edge of the neck. The plug 62 is preferably provided with a pair of openings 64 and 65 of the shape illustrated in Fig. 2. If desired, a glass tube 56 may be extended through opening 65, the head 67 of the tube resting within the shallow recess at the upper side of opening 65.

After the plug 62 has been placed in position, I preferably secure an inner clamping ring 68 in the position shown in Fig. 2, the lower edge of the metal ring being clamped about the lower bead 61, while the upper flange 69 rests upon the ledge or lip 63 of plug 62. In this manner the plug 62 is clamped in tight sealing position within neck 60.

I next place a thin flexible sealing disk 70 of rubber, or other suitable material, upon the top of plug 62 so that the edges of the disk rest upon the horizontal flange 69 of clamping ring 68. It will be observed that the sealing disk 70 is substantially co-extensive with the top portion of the rubber plug 62.

Over the flexible seal 70, I place a metal disk 71 which clamps the peripheral edge of the flexible member 70 firmly against the horizontal flange 69 of the inner ring 68. The metal cap 72 is then placed over the flexible seal 70 and the metal disk 71, as shown more clearly in Fig. 2,

and the lower edge portions 73 are spun under the lower shoulder of inner ring 68. If desired, the cap 72 may be provided with a tear flap 74. The metal of cap 72 is preferably thin so that the user may grasp flap 74 and by exerting tension thereon, tear a strip of metal away along the side of the cap, thus permitting the cap to be removed. I have found the use of certain aluminum alloys satisfactory for the construction of the inner ring 68, disk 71 and cap 72, although it will be understood that other suitable metals may be used.

In the metal cap 72 I preferably form two slits 75 which extend entirely through the metal and which are spaced slightly inwardly of the neck of the tear flap 74. As shown more clearly in Figs. 1 and 3, the openings 75 extend from a point adjacent the tear flap 74 up to the curved portion of the cap. Below the curved portion of the cap and extending along the sides thereof are two parallel indentations or grooves not extending entirely through the metal but forming weakened lines along which the tear will occur. Preferably, the weakened lines 76 are spaced slightly inwardly from the cuts 75 so that a small metal area extends between the ends of opening 75 and grooves 76. With this construction, it is found that the metal tears evenly and accurately along the lines 76.

One major difficulty in the use of metal caps such as 72 has been the danger of cutting the operator with the jagged edges of the metal after the tear flap has been drawn. After the tear flap has been drawn, it is still necessary to spread the cap in order to remove it from engagement with the bottle neck and particularly from engagement with the lower portion of clamping ring 78 which extends about the lower rib 61. I have found that this danger can be readily obviated, and a very quick and easy removal of the cap effected by forming a V-shaped notch 77 in the opposite side of the cap from the tear flap 74, as shown more clearly in Figs. 1 and 3. I prefer to have the notch 77 substantially diametrically opposed to a line equi-distant from the grooves 76. With this construction, the cap 72 can be spread apart very readily to the position shown in Fig. 7. At the same time the two halves of the cap do not fall apart but are held together by the rear wall of the cap forming a hinge 78. The portions of the cap to be discarded then are only the tear flap and the walls forming the body of cap 72.

In the operation of the invention, the ring 68 is placed in position, as shown in Fig. 2, and the

lower portion of the ring clamped under the lower rib 61. The flexible element 70 of rubber, or other suitable material, is then placed in the position shown in Fig. 2 with the edges of the rubber 5 lying on the top flange of the clamping ring 68. The metal disk 71 is then placed in position so that its peripheral portion tends to grip the edge of the rubber 70 between it and the top flange of ring 68. The cap is then forced into place by 10 mechanism of well-known construction and the lower edge of the cap spun about the lower edge of ring 68, as shown more clearly in Fig. 2. In this position, the outer edge of the flexible member 70 is tightly gripped between the plate 71 and 15 the horizontal top flange of the ring member 68.

To remove the sealing means it is only necessary for the operator to grasp the tear flap 74 and to draw it laterally. The break occurs along the slots 74 and then along the groove lines 76. 20 After the tear has been completed through the side of the cap, the operator grasps the sides and spreads them laterally. The notch 77 causes the portion between the V-slot thereof and the curved edge of the cap to break readily, and the two 25 halves of the cap may be swung apart on hinge 78 to free it from engagement with the ring 68, as shown more clearly in Fig. 7. The disk 71 may then be removed and the rubber disk 70 lifted out of position. The confining ring 68 maintains 30 the plug 62 in position during the subsequent operation of removing the liquid from the container, an operation which is well-known and need not be described herein.

While in the foregoing description I have set 35 forth certain specific sealing devices for the purpose of illustration, it will be understood that such devices can be modified greatly without departing from the spirit of my invention.

The foregoing detailed description has been

given for clearness of understanding only, and no unnecessary limitations should be understood therefrom, but the appended claims should be construed as broadly as permissible, in view of the prior art.

I claim:

1. In combination with a container having an opening and a closure for said opening, said closure having at least one opening extending therethrough, a clamping ring engaging said container and confining said closure in position, a flexible sealing disk extending over said closure and a portion of said clamping ring, and means for confining the peripheral edge portion of said flexible sealing disk against said clamping ring. 15

2. In combination with a container having a neck with its opening closed by a plug, said plug having at least a pair of openings therethrough, a clamping member secured to said bottle neck and engaging said plug, a sealing member extending over said plug and a portion of said clamping member, a metal disk extending over said sealing member and confining the peripheral portion of said sealing disk between it and said clamping member, and a cap extending over said 25 metal disk.

3. In combination with a container having its neck closed by a plug, said plug having an annular rubber flange resting on the top of said neck, the neck of said bottle being provided externally 30 with a bead, a clamping member engaging the bead of said bottle neck and having a horizontal flange extending over said plug and having its peripheral portion resting on said horizontal flange, a metal disk above said sealing disk and 35 confining said sealing disk between it and said horizontal flange, and a metal cap enclosing said metal disk and said clamping member.

HARRY N. FALK.
